UNITED STATES PATENT OFFICE.

ROBERT F. REX, OF ANDOVER, OHIO.

FOLDING FLOOR FOR RAILWAY-CARS.

1,351,125.

Specification of Letters Patent. Patented Aug. 31, 1920.

Application filed December 8, 1919. Serial No. 343,269.

To all whom it may concern:

Be it known that I, ROBERT F. REX, a citizen of the United States, residing at Andover, in the county of Ashtabula and 5 State of Ohio, have invented certain new and useful Improvements in Folding Floors for Railway-Cars, of which the following is a specification.

This invention relates to an improvement 10 in railroad cars, and more particularly to refrigerator cars.

In handling perishable goods, such as milk, cream, vegetables, and the like, the capacity of the car is seldom reached, be- 15 cause of the difficulty in loading the car so that the entire tonnage capacity of the car may be utilized, as in loading a car of milk or cream in can containers the capacity of the car is restricted to the floor space only.

20 In articles such as melons, etc., the extreme frailty of the melons will not allow of many piled upon each other.

In order to overcome this difficulty, my invention has for its principal object the pro- 25 viding of a second floor for the car which is situated at a convenient distance from the bottom or regular floor of the car.

Another object is to provide a folding 30 floor that may be folded up in sections against the sides of the car walls when not in use, or when the first floor is being loaded.

A still further object of the invention is to provide supporting legs, and means for 35 holding the folding floor in proper position when lowered in position for loading.

With these objects in view, the invention consists in certain novel features of construction, and combinations, and arrangements of parts, as hereinafter set forth, and 40 pointed out in the claim.

In the accompanying drawings, Figure 1 is a top view plan of the folding floor. Fig. 2 is a sectional end view of a car showing 45 the manner in which the folding floor is supported and folded up when not in use. Fig. 3 is a detailed view showing the supporting leg and the T-iron used in supporting the opposite portion of the folding floor, which is not provided with a support-

ing leg. Fig. 4 is a detailed sectional view showing the manner in which the folding floor may be retained in a folded position. Fig. 5 is a detailed view showing the latching means for the folding floor.

55 By referring to Fig. 1, it will be seen that 1 represents the side walls and ends of a car. The second floor of the car is formed in sections; sections 2 having supporting means to support the inner ends 3 of the sections 2. This supporting is accomplished by the use of a folding leg 4.

60 By referring to Fig. 2 it will be seen that this folding leg 4 is secured to the sections 2, near the inner ends 3. The pivot portion 65 of the folding leg 4 is secured within a housing 5 by means of a bolt 6. When the folding leg 4 is in the proper position for supporting the floor sections, above referred to, the weight of the floors will 70 cause the weight to be carried at point 7 of the folding leg 4, thereby holding the leg from taking any other position than a perpendicular one. The wall ends of sections 2 and 8 are secured to the side walls 75 by hinges 15. The angle iron 16 is secured to the side walls and forms a support for said ends.

76 It will be seen by referring to Fig. 2 that the sections 8 of the folding floor are op- 80 posite the sections 2. When the sections 8 are lowered, they are held in position at the inner ends 9 by means of an inverted T-iron 10 attached to the sections 2. The flange 11 of the inverted T-iron provides a 85 seat upon which rests the inner ends 9 of the sections 8.

If desired, the sides may be provided with a like securing means.

85 By referring to Fig. 4, 12 are staples se- 90 cured to the car wall 1 by any suitable means; when the sections are folded up, these staples 12 extend through openings 13 in the sections 2 and 8.

95 By referring to Fig. 5, it will be seen that I have provided a hook 14 to pass within each staple 12, thereby securely holding the sections 2 and 8 in an upright position against the walls 1.

100 Having thus described my invention, what

I claim and desire to secure by Letters Patent is:

In a device of the class described, having in combination with a railway car, a second floor formed in sections, the outer edge of each section hinged to the sides of said car, an L-iron secured to the sides of the car directly underneath the hinged edges, fold-

ing legs attached to the inner edges of said sections, each leg attached to an offset pivot 10 portion.

In testimony whereof I affix my signature.

ROBERT F. REX.
